United States Patent Office.

HENRY M. RITTER, OF CINCINNATI, OHIO, ASSIGNOR TO M. GREENWOOD
AND COMPANY, OF THE SAME PLACE.

Design No. 2,658, dated May 21, 1867.

DESIGN FOR A PIANO-STOOL.

The Schedule referred to in these Letters Patent and making part of the same.

TO ALL WHOM IT MAY CONCERN:

Be it known that I, HENRY M. RITTER, of Cincinnati, Hamilton county, and State of Ohio, have invented a new and ornamental Design for a Piano-Stool, which design is represented in the accompanying drawings, making part of this specification. In the accompanying drawings—

I claim herein as new and of my invention—

The design for a piano-stool, substantially as represented in the accompanying drawings.

In testimony of which invention I hereunto set my hand.

HENRY M. RITTER.
